United States Patent Office

Des. 196,536
Patented Oct. 8, 1963

196,536

RING BOX

Jerome Shiffman, 128 Carthage Road, Scarsdale, N.Y.

Filed Jan. 21, 1963, Ser. No. 73,260

Term of patent 7 years

(Cl. D58—11)

FIG. 1.

FIG. 2.

FIG. 3.

FIG. 4.

FIG. 1 is a top plan view of a ring box, showing my new design;

FIG. 2 is a side elevational view, the opposite side being a mirror image thereof;

FIG. 3 is a front elevational view thereof; and

FIG. 4 is a rear elevational view thereof.

I claim:

The ornamental design for ring box, as shown and described.
